UNITED STATES PATENT OFFICE.

GEORGE H. STEVENSON, OF RYE, NEW YORK, ASSIGNOR TO WESTERN ELECTRIC COMPANY, INCORPORATED, OF NEW YORK, N. Y., A CORPORATION OF NEW YORK.

PROTECTIVE MEANS FOR ELECTRIC CIRCUITS.

Application filed May 25, 1921. Serial No. 472,365.

To all whom it may concern:

Be it known that I, GEORGE H. STEVENSON, a subject of the King of Great Britain, having taken out first papers in the United States, residing at Elmwood Avenue, Rye, in the county of Westchester, State of New York, have invented certain new and useful Improvements in Protective Means for Electric Circuits, of which the following is

10 a full, clear, concise, and exact description.

This invention relates to protective means for electric circuits and more particularly it relates to protective means for high frequency or radio circuits in which vacuum tubes of the 3-electrode type are employed for amplifying, modulating, generating or detecting signaling currents.

As is well-known in the art vacuum tubes of the 3-electrode type comprise an anode, 20 a cathode and a grid or control electrode for controlling the space current between the other two electrodes. These tubes are designed to work between certain limits of anode-cathode space current and a variation 25 of the space current outside the permissible range is highly undesirable particularly if the current at any time exceeds the allowable maximum, for in such case the tube is liable to blue haze or blow up or otherwise be rendered useless. The intensity of 30 the space current for a given tube depends first, upon the anode-cathode potential; second, upon the value of the voltage supplying the heating current for the cathode; 35 and third, upon the potential of the grid with respect to the cathode. The variation of any one of these voltages beyond its permissible range of variation may be sufficient to increase the space current to such an 40 extent that the tube will be completely destroyed or rendered useless. To prevent such a possibility is particularly important in signaling circuits such as radio circuits wherein high power vacuum tubes capable 45 of handling from .1 kilowatt to one kilowatt or more of output power are employed which are generally worked with almost the maximum allowable space current to obtain the greatest amount of power output 50 therefrom.

In accordance with this invention means are provided responsive to variations in the space current of such a tube to render the tube inoperative whenever the space cur-

rent tends to increase beyond the desired 55 range. In the preferred form of this invention a 2-electrode tube with a filamentary cathode and an anode is employed having its cathode connected in the anode-cathode circuit of the tube to be protected 60 and having its anode-cathode circuit completed through a source of voltage and the solenoid of a relay which when energized serves to disconnect from the tube to be protected one of its energizing sources of 65 voltage. Such an arrangement is especially advantageous in radio or other ultra-audio frequency signaling circuits, since such protective means does not require the insertion of an inductance element such as a winding 70 of a relay or electro-magnet in any part of the high frequency circuit of the tube to be protected. Such an insertion would be quite objectionable since it would seriously affect the tuning of the high frequency circuits, 75 which are generally of a highly selective nature.

This invention will be better understood by reference to the following detailed description taken in connection with the accompanying drawings in which Fig. 1 represents an embodiment of this invention in which the 2-electrode tube responsive to changes in the space current of the tube to be protected, controls a solenoid for disconnecting from the tube to be protected its source of space current; while Fig. 2 represents a modification of Fig. 1 in which a solenoid controls the connections of the source of voltage for supplying heating 85 current to the cathode of the tubes to be protected. Fig. 3 illustrates a curve showing the value of the space current in a 2-electrode tube for different values of the heating current for its cathode.

Referring more particularly to Fig. 1, a radio transmitting system is disclosed therein which is adapted to supply to the antenna 10 high frequency oscillations modulated in accordance with the signalling oscillations from the transmitter 11. The principal features of this radio transmitting system have been described in detail in a publication by Craft and Colpitts in an article on Radio Telephony published 105 in vol. 38, page 360 of the American Institute of Electrical Engineers. For the purposes of this specification the system may

be briefly described as comprising two vacuum tubes 12 and 13 connected in parallel and acting as a source of ultra-audio frequency oscillations which may be, for example, of the order of one million cycles per second. Vacuum tubes 14 and 15 are two amplifiers connected in parallel having their common input circuit associated with the transmitter 11 by a transformer 16 and their output circuit so associated with the generators 12 and 13 that the tubes 12 and 13 act both as generator and modulator tubes. The high frequency oscillations from tubes 12 and 13 modulated in accordance with the signals from source 11 are impressed on the antenna 10 by the transformer 17.

Tubes 12, 13, 14 and 15 which are of the well-known 3-electrode type comprise cathodes 18, 19, 20 and 21; anodes 22, 23, 24 and 25 and control electrodes 26, 27, 28 and 29, respectively. The four cathodes are supplied in parallel with heating current from a common source of voltage or battery 30. 31 is a DC generator or other source of voltage for supplying the desired anode-cathode voltage for these four tubes. The connection of one side of generator 31 to the cathodes 18 to 20 inclusive may be traced through conductors 32, 33 and 34 to each of the cathodes. The other side of generator 31 is connected to anode 24 by conductor 35, movable contact 36 of relay 37, conductors 38, 39, cathode 40 of a 2-electrode tube 41 to anode 24. The connection of generator 31 to anode 25 may be traced through movable contact 36, the cathode 42 of the 2-electrode tube 43. The connection of the generator to anodes 22 and 23 may be similarly traced through the cathodes 45, 46 of the two 2-electrode tubes 47 and 48 respectively. From these connections it is apparent that the space current flowing through each of the 3-electrode tubes must traverse the filamentary cathode of one of the 2-electrode tubes. Each of the 2-electrode tubes 41, 43, 47 and 48 should be so designed, when its corresponding 3-electrode tube is traversed by its normal average space current, that the electron emission of the cathode of each 2-electrode tube will be only a fractional part of its maximum electron emission. Referring to Fig. 3 the curve 49 illustrates the various values the electron emission in the cathode will have when its heating current is varied. In this figure the ordinates represent various values of space current and the abscissæ represent various values of the filament heating current. Each of the 2-electrode tubes should be preferably so designed that when its cathode is traversed by the normal space current of its tube to be protected that the space current of the 2-electrode tube has a value approximately corresponding

to the value where the dotted line intersects curve 49. If such an adjustment is made it can be readily seen that a small change in the heating current of the cathode will produce a much greater change in the space current of the 2-electrode tube.

The 2-electrode tubes 41, 43, 47 and 48 are supplied with space current from a common source of voltage 50. One side of source of voltage 50 is connected to cathodes 42, 45 and 46 by leads 35, 38, while the other side of this source is connected to the anodes 51, 52, 53, 54, by relay winding 55, lead 56, relay winding 57 and lead 58, relay winding 59 and lead 60, and relay winding 61 and lead 62 respectively. Relay 55 should be so adjusted that its contacts will remain open as long as tube 14 is supplied with normal space current. When, however, the circuit conditions of tube 14 should so change that the space current thereof exceeds the allowable maximum, the heating current of cathode 40 will thereby be increased, which will produce a much greater increase in the space current of tube 41 which flows through relay 55. This increase in the space current of tube 41 should be sufficient to cause relay 55 to pull up its movable contact 63. The closing of movable contact 63 energizes relay 37 from battery by closing the circuit from battery, winding relay 37, conductor 64, movable contact 63 and conductor 65 to the other side of the battery and relay 37. In pulling up its contact 66, the relay locks itself up over a circuit completed by the key 67 and will remain locked up until key 67 is manually operated. Relay 37 also pulls up its movable contact 36 to disconnect generator 31 from all of the 3-electrode tubes thereby rendering the 3-electrode tubes inoperative until the system has been personally supervised by an attendant to correct the defect in the system which resulted in the objectionable increase in the space current of tube 14.

In the same manner if the space current of tube 15 should be increased beyond its allowable maximum the 2-electrode tube 43 will cause relay 57 to pull up its movable contact thereby energizing relay 37 to disconnect the source of voltage 31. Relays 51 and 60 will operate similarly in response to increases in the space current of tubes 12 and 13 respectively.

The modification illustrated in Fig. 2 is somewhat similar to that of Fig. 1 except that a switching relay 70 is provided for disconnecting the source of voltage 30 from the cathodes of the tubes 12 to 15 whenever their space current exceeds the allowable maximum. Each of the tubes 12 to 15 has associated therewith one of the 2-electrode tubes 71, 72, 73 and 74, the cathode of which is traversed by the space

current from the associated 3-electrode tube. Instead of providing a relay individual to each 2-electrode tube as in Fig. 1 for controlling the relay which disconnects the 5 source of voltage, the system of Fig. 2 employs a single relay 75 common to the four 2-electrode tubes 71 to 74 inclusive. Whenever the space current of one of the 10 2-electrode tubes is increased due to an undesirable increase in the space current of its corresponding 3-electrode tube, relay 75 by obvious connections will be energized to pull up its movable contact 76 and energize the relay 70 which serves to break the 15 connections between the cathodes and their source of heating current 30.

The above described arrangement for regulating a 3-electrode tube by a 2-electrode tube which has its cathode traversed by 20 space current of the 3-electrode tube is especially advantageous in ultra-audio frequency circuits, since such regulating means does not require the insertion of an inductance element such as a winding of a 25 relay in a circuit traversed by alternating currents of ultra-audio frequencies. Inasmuch as a filamentary cathode such as 46 of tube 48 is substantially non-inductive, the insertion of such a cathode in the output 30 circuit of tube 13 does not interfere with the oscillatory character of the output circuit, such as changing the tuning thereof.

Although this invention has been described above in connection with an ultra-audio circuit it is to be understood that this invention may be beneficially employed in other types of circuits employing devices to be protected from excessive currents or voltages. It is also to be understood that 40 methods within this invention other than those specifically described above may be employed if desired for rendering the 3-electrode tubes inoperative whenever their space current tends to increase beyond the 45 allowable maximum.

What is claimed is:

1. In combination, a vacuum tube having an anode and a cathode, a second vacuum tube having a filamentary cathode and a second electrode, a source of voltage for said first tube, and external connections for said second cathode, said external connections being connected in series with said anode, said first cathode and said source.
2. In combination a vacuum tube having an anode and a cathode, a second vacuum tube having a filamentary conductor therein and a second electrode, a source of voltage, and connections between said source and said anode and cathode, one of said connections including said filamentary conductor.
3. In combination a vacuum tube having an anode and a cathode, a second tube having an anode and a cathode, a common source of voltage for supplying space cur-

rent to said first tube and supplying heating current to said second cathode, and a second source of voltage for supplying space current to said second tube.

4. In combination, a vacuum tube having 70 an anode, a cathode and a control electrode, a second vacuum tube having a plurality of electrodes, one of which has a plurality of external terminals, a connection between said anode and one of said terminals and 75 a connection between said cathode and another of said terminals.

5. In combination, a vacuum tube having 80 an anode and a cathode, a source of voltage, an electron discharge path, and connections from said source for supplying heating current to said cathode, one of said connections being made through said electron discharge path, whereby the heating current supplied to said cathode flows through said discharge path.

6. In combination a vacuum tube having 85 an anode and a cathode, a source of space current for said tube, a second vacuum tube having an anode and a cathode, connections 90 whereby the temperature of said second cathode is responsive to the space current of said first tube, and a work circuit responsive to the resulting changes in the space current of said second tube.

7. In combination, a vacuum tube, a second vacuum tube having an anode and a cathode, a source of heating current for said cathode, connections whereby the heating current of said cathode is made responsive 100 to variations in a characteristic of said first tube, and means responsive to the resulting changes in the space current of said second tube for regulating said first tube.

8. In combination, a vacuum tube, a second vacuum tube having an anode and a cathode, a source of heating current for said cathode, connections whereby the heating current to said cathode is made responsive 105 to variations in a characteristic of said first tube, and means responsive to the resulting change in the space current of said second tube for rendering said first tube inoperative.

9. In combination, a vacuum tube, a source 110 of voltage for said tube, a second vacuum tube having an anode and a cathode, means for making the heating current supplied to said cathode responsive to changes in a characteristic of said first tube, and an electro-magnetic switch responsive to the resulting change in the space current of said second tube for disconnecting said source from said first tube.

10. In combination, a vacuum tube comprising an anode and a cathode, a second vacuum tube having an anode and a cathode, means whereby heating current for said second cathode is dependent upon the anode-cathode current of said first tube, a solenoid 125

traversed by space current from said second tube and circuit connections for said first tube controlled by said solenoid.

11. In combination, a vacuum tube having an anode, a cathode and a control electrode, a source of space current for said tube, means for supplying signaling potentials to said control electrode, and a second vacuum tube responsive to variations in a characteristic of said first tube for rendering said first tube inoperative.

12. In combination, a vacuum tube having an anode and a cathode, a second vacuum tube having a plurality of electrodes, means for controlling the temperature of an electrode of said second tube in response to variations in a characteristic of said first tube, and means responsive to changes in said temperature for regulating said first tube.

13. In combination, a vacuum tube having an anode and a cathode, a second vacuum tube having an anode and a filamentary cathode, connections for causing the space current of said first tube to traverse said filamentary cathode for heating the same, said connections being such that the electron emission from said filamentary cathode is only a fractional portion of its maximum emission for a given anode-cathode voltage and means responsive to the discharge characteristics of said second tube for controlling said first tube.

14. In combination, a vacuum tube having an anode, a cathode, and a control electrode, a source of voltage for said tube, means for supplying signaling potentials to said tube, a non-inductive element responsive to a condition of said tube, and means responsive through the intermediary of said element to an excessive current in said tube for disconnecting said source from said tube.

15. In combination, a vacuum tube having an anode, a cathode and a control electrode, means for supplying to said tube signaling potentials to be repeated, a non-inductive element traversed by current varying in intensity in response to variations in a characteristic of said tube, and means operating upon an increase in the current through said element for rendering said tube inoperative.

16. An ultra-audio frequency system comprising a vacuum tube having an anode, a cathode and a control electrode, a second vacuum tube having a cathode traversed by heating current of an ultra-audio frequency dependent upon a characteristic of said first tube and means responsive to said second tube for regulating said first tube.

17. An ultra-audio frequency system comprising a vacuum tube having an output circuit, a source of space current for said tube, connections for causing said output circuit to be traversed by currents of an ultra-audio frequency, a second tube having

an anode and a filamentary cathode, said cathode being serially connected in said output circuit whereby the electron emission of said cathode is responsive to variations in the space current of said first tube, and means responsive to variations in the electron emission of the cathode of said second tube for controlling the circuit connections of said first tube.

18. In combination, a plurality of vacuum tubes each having an anode, a cathode and a control electrode, a common source of space current for said tubes, and a two-electrode tube responsive to a condition of one of said first tubes for rendering all of said first tubes inoperative.

19. In combination, a plurality of vacuum tubes, each comprising an anode, a cathode and a control electrode, a common source of space current for said tubes, a common source of heating current for said cathodes, and an additional vacuum tube responsive to a condition of only one of said tubes for controlling the condition of all of said first tubes.

20. In combination, a plurality of vacuum tubes each having an anode, a cathode and a control electrode, a common source of space current for said tubes, a common source of heating current for said cathodes, an additional vacuum tube having a cathode traversed by heating current varying in accordance with a condition of one of said first tubes, and means responsive to said additional tube for disconnecting one of said sources from all of said first tubes.

21. In combination a plurality of tubes each having an anode, a cathode and a control electrode, an additional vacuum tube individual to each of the first set of tubes and responsive to a condition of its associated tube of the first set and means responsive to one of said additional vacuum tubes for controlling said first-mentioned tubes.

22. In combination, a vacuum tube, means for supplying alternating currents to said tube, a second vacuum tube, connections between said tubes for causing a change in a condition of said first tube to produce a greater change in a condition of said second tube, and a circuit interrupter controlled by said second tube.

23. In combination, a line, means for supplying high frequency waves modulated by signals to said line, and means responsive to said modulated waves for determining when said modulated waves will be transmitted to said line.

24. In combination, a line, means for supplying high frequency waves modulated by signals to said line, and a circuit interrupter responsive to a condition of said waves for determining when modulated waves will be transmitted to said line.

25. In combination, a line, means for sup-

plying high frequency waves modulated by signals to said line, a vacuum tube energized by said waves, and a circuit interrupter controlled by said tube for determining 8 when modulated waves will be transmitted to said line.

26. A system comprising a plurality of tubes and a power supply in common thereto in combination with means individual to each tube actuated by excessive space current through that tube to cut off the power supply of the entire system. 10

27. A signaling system comprising a plurality of vacuum tubes, a common source of energizing current for said tubes, means individual to each tube and actuated when abnormal conditions are present in each tube and means responsive to said first means for rendering all of said tubes inoperative. 15

28. In combination, a vacuum tube having an anode and a cathode, means for supplying energizing current to said cathode, means for supplying space current between said anode and cathode and means responsive to an excessive space current for rendering one of said means inoperative. 20

29. In combination, an electric discharge device having an anode and a cathode, a source of current for heating said cathode, a source of current for supplying space current between said anode and cathode and means responsive to excessive current in said device for disconnecting one of said sources. 30

In witness whereof, I hereunto subscribe my name this 19th day of May A. D., 1921. 35

GEORGE H. STEVENSON.

DISCLAIMER.

1,506,275.—*George H. Stevenson, Rye, N. Y. PROTECTIVE MEANS FOR ELECTRIC CIRCUITS.* Patent dated August 26, 1924. Disclaimer filed May 5, 1926, by the patentee, assignee, *Western Electric Company, Incorporated*, consenting.

Hereby enters this disclaimer to the said claims of said Letters Patent which are in the following words, to wit:

“28. In combination, a vacuum tube having an anode and a cathode, means for supplying energizing current to said cathode, means for supplying space current between said anode and cathode and means responsive to an excessive space current for rendering one of said means inoperative.

“29. In combination, an electric discharge device having an anode and a cathode, a source of current for heating said cathode, a source of current for supplying space current between said anode and cathode and means responsive to excessive current in said device for disconnecting one of said sources.”
